(57) **CLAIM**

The ornamental design for a zipper pull, as shown and described.

DESCRIPTION

FIG. 1 is a front view of a zipper pull according to the design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a bottom perspective view thereof;

FIG. 8 is a top perspective view thereof; and,

FIG. 9 is a bottom perspective view thereof shown in an environment of use.

The broken line showing of the zipper slider in FIG. 9 is for the purpose of illustrating portions of the environmental structure and forms no part of the claimed design.

1 Claim, 9 Drawing Sheets
